[57] CLAIM

The ornamental design for a “set of jazz beads”, as shown and described.

DESCRIPTION

FIG. 1 is a perspective view of a set of jazz beads showing my new design in a position of use, the broken line showing of a necklace is for illustrative purposes only and forms no part of the claimed design;

FIG. 2 is a perspective view of one bead which simulates a clarinet;

FIG. 3 is a top plan view of FIG. 2;

FIG. 4 is a front elevational view of FIG. 2;

FIG. 5 is a side elevational view of FIG. 2, the opposite side view being a mirror image;

FIG. 6 is a rear elevational view of FIG. 2;

FIG. 7 is a bottom plan view of FIG. 2;

FIG. 8 is a perspective view of one bead which simulates a saxophone;

FIG. 9 is a top plan view of FIG. 8;

FIG. 10 is a front elevational view of FIG. 8;

FIG. 11 is a side elevational view of FIG. 8, the opposite side being a mirror image;

FIG. 12 is a rear elevational view of FIG. 8;

FIG. 13 is a bottom plan view of FIG. 8;

FIG. 14 is a perspective view of one bead which simulates a drum;

FIG. 15 is a top plan view of FIG. 14;

FIG. 16 is a front elevational view of FIG. 14;

FIG. 17 is a left side elevational view of FIG. 14;

FIG. 18 is a right side elevational view of FIG. 14;

FIG. 19 is a bottom plan view of FIG. 14;

FIG. 20 is a rear elevational view of FIG. 14;

FIG. 21 is a perspective view of one bead which simulates a piano;

FIG. 22 is a top plan view of FIG. 21;

FIG. 23 is a left side elevational view of FIG. 21;

FIG. 24 is a front elevational view of FIG. 21;

FIG. 25 is a rear elevational view of FIG. 21;

FIG. 26 is a bottom plan view of FIG. 21;

FIG. 27 is a right side elevational view of FIG. 21;

FIG. 28 is a perspective view of one bead which simulates a trumpet;

FIG. 29 is a top plan view of FIG. 28;

FIG. 30 is a front elevational view of FIG. 28;

FIG. 31 is a left side elevational view of FIG. 28;

FIG. 32 is a right side elevational view of FIG. 28;

FIG. 33 is a rear elevational view of FIG. 28; and,

FIG. 34 is a bottom plan view of FIG. 28.
